US0D1101140S

(12) **United States Design Patent** (10) **Patent No.:** **US D1,101,140 S**
(45) **Date of Patent:** **** Nov. 4, 2025**

(54) **SINGLE EYE SHIELD**

(71) Applicant: **MarketHATCH Co., Inc.**, Akron, OH (US)

(72) Inventor: **Paul A. Joyce**, Sharon, OH (US)

(73) Assignee: **MarketHATCH Co., Inc.**, Akron, OH (US)

(**) Term: **15 Years**

(21) Appl. No.: **29/959,691**

(22) Filed: **Aug. 27, 2024**

(51) LOC (15) Cl. **24-02**

(52) U.S. Cl.

USPC **D24/172**

(58) **Field of Classification Search**

USPC D24/110.2, 170, 172, 185–187, 231, 232, D24/140, 158–160, 120, 184, 137; D15/199; D16/100, 130, 136, 301; D21/302, 304, 307, 308; D8/349, 352; D1/121, 128, 130
